United States Patent Office

Des. 219,878

Patented Feb. 9, 1971

219,878

RACK FOR JEWELRY OR OTHER ARTICLES

Gladys Flores Rowland, 1327½ N. Hayworth Ave.,
Los Angeles, Calif. 90046

Filed Sept. 29, 1969, Ser. No. 19,333

Term of patent 14 years

Int. Cl. D6—99

U.S. Cl. D33—3

FIG. 2.

FIG. 1.

FIG. 1 is a front elevational view of my rack for jewelry or other articles, showing my new design; and FIG. 2 is a side elevational view.

I claim:

The ornamental design for a rack for jewelry or other articles, as shown.
